UNITED STATES PATENT OFFICE.

AUGUSTO CAPRA AND LODOVICO CONTRI, OF NEW YORK, N. Y.

TOY.

1,047,381.

Specification of Letters Patent. Patented Dec. 17, 1912.

Application filed May 23, 1911. Serial No. 629,309.

To all whom it may concern:

Be it known that we, AUGUSTO CAPRA and Lodovico Contri, citizens of the Italian Monarchy, and residents of the city, county, 5 and State of New York, have invented certain new and useful Improvements in Toys, of which the following is a specification.

This invention relates to improvements in toys and more particularly to an improved 10 device for the spinning of tops.

The object of the invention is to provide an improved toy for spinning a top having a neat appearance and one which can be produced at low cost.

15 In the drawing illustrating the invention and accompanying this specification Figure 1 is a perspective view of the toy and Fig. 2 is a side view illustrating the mode of operation.

20 The toy comprises three general parts, a holder 3, a top 4 and a string 5. The holder has a handle 6 and a ring 7 forming an aperture 8 and the ring is provided with holes 9 and 10 oppositely disposed. The top 25 comprises a head 12 and a shank 13 provided with grooves 14. The head carries a pin 15. The one end of the string 5 is formed into a loop 16 and the other end carries a button 17.

30 In operation the loop 16 of the string is passed through the hole 9 from the outside of the ring 7 and is then drawn up through the aperture 8. The loop is then hooked over the pin 15 and the string wound around 35 the shank 13 of the top in the grooves 14. Fig. 1 illustrates the beginning of the operation showing the loop 16 hooked over the pin 15. When nearly all of the string has been wound tightly around the top, the 40 latter is inserted in the aperture 8 as shown in Fig. 2. It will be noted that the aperture 8 is of larger diameter than the shank of the top. The toy is now ready for the spinning of the top. The holder is held in 45 the left hand and with the right hand the operator takes hold of the button 17 and by a quick pull in direction of the arrow 18 un- 50 winds the string from the top and lifts the top from the holder and simultaneously therewith unwinds the string and the top is given its rotary or spinning movement. By reason of the fact that the string is

wound from the top of the shank and to the bottom and thereafter passed through the hole 9, it will be clear that a positive upward movement of the top, prior to the rotary movement, is assured to free the top from the holder, furthermore, by reason of this upward movement of the top, the loop 16 of the string is automatically pulled down, 60 so to speak, and disengaged from the pin 15, as is clearly understood from the position of the parts in Fig. 2 where the dotted lines indicate the position of the top the moment the latter leaves the holder. 65

The operation is greatly facilitated because the aperture 8 permits free movement of the top as the latter leaves the holder and also permits the top to be drawn sharply to one side giving a quicker initial movement. 70

The grooves 14 enable the string to be wound orderly and tightly around the shank 13 so as to set the top spinning quickly.

In case the operator is left handed the 75 operation is begun by passing the loop 16 through the hole 10 and then up through the aperture 8.

We claim:

The combination of a holder having a 80 ring provided with oppositely disposed holes in the wall thereof, a top having a head adapted to rest on said ring and provided with a grooved shank adapted to fit freely within the same, a downwardly projecting 85 pin in the said head of the top and a string for spinning said top and for lifting the same out of the ring, the said string being passed through one of the said holes in the ring and wound in the grooves on the said 90 shank, the one end of the string having a loop adapted to engage the said pin, whereby by the said string is wound on the shank from the head of the top and downward to cause a positive upward movement of the 95 top when the string is pulled to free the top from the holder and to rotate said top.

Signed at New York, N. Y. this 9th day of May, 1911.

AUGUSTO CAPRA.
LODOVICO CONTRI.
